UNITED STATES PATENT OFFICE.

CARL AICHLERGER, OF WESTWOOD, NEW JERSEY, ASSIGNOR TO ANSONIA CLOCK CO.,
OF BROOKLYN, NEW YORK, A CORPORATION OF CONNECTICUT.

DESIGN FOR A MIRROR OR PICTURE FRAME.

Application filed February 28, 1922. Serial No. 943. Term of patent 14 years.

To all whom it may concern:

Be it known that I, CARL AICHLERGER, a citizen of the United States, and a resident of Westwood, county of Bergen, and State of New Jersey, have invented a certain new and ornamental Design for a Mirror or Picture Frame, of which the following is a specification, reference being had to the accompanying drawings, forming a part thereof.

In the drawings

Fig. 1 is a front elevation of a frame, illustrating my new and ornamental design, and

Fig. 2 is a side elevation of the same.

What I claim and desire to secure by Letters Patent, is

The ornamental design for a mirror or picture frame as shown.

CARL AICHLERGER.
